UNITED STATES PATENT OFFICE.

HIRAM HOLDEN, OF MANCHESTER, NEW HAMPSHIRE.

BINDING DEVICE.

Application filed June 4, 1923. Serial No. 643,456.

To all whom it may concern:

Be it known that I, HIRAM HOLDEN, a citizen of the United States, and resident of Manchester, in the county of Hillsborough and State of New Hampshire, have invented certain new and useful Improvements in Binding Devices, of which the following is a specification.

My present invention relates to a device 10 for facilitating the spacing of a folded edging to a strip of leather.

In the shoe industry it has been found desirable under certain conditions to piece out certain pieces of the leather with an edging 15 of other material folded longitudinally and disposed on each side of the leather. Such a structure is illustrated in my United States Patent No. 1,395,277. This invention has to do specifically with a device which may be 20 attached to an ordinary sewing machine to insure that the leather and the extension strip bear the proper relation to each other when the stitching element sews the two together.

25 The primary object of my invention is the provision of such means which may be as near automatic in its operation as possible, requiring the minimum amount of attention, which will have universal adjustments to 30 adapt it to the various types of machines now in use, and which may have an adjustment providing for the leather extending varying distances into the folded strip.

Obviously this invention is applicable in 35 its principle to other uses than the sewing of an extension strip to a leather shoe upper, as disclosed in the above mentioned patent, although the invention is particularly applicable to this phase of the shoe industry.

40 I have illustrated a preferred form of device in the drawings which has been found to satisfactorily produce the desired results, but it is to be understood that this is merely illustrated of one form and is not to be taken 45 as limiting the scope of the invention.

In the drawings:

Figure 1 is a plan view of one embodiment of my invention in its relation to the presser foot of a sewing machine.

50 Fig. 1^a is a detail view of the nose element.

Fig. 2 is a front elevation of the device of Fig. 1.

Fig. 3 is an end elevation.

Fig. 4 is a rear view.

55 Fig. 5 is a detail of the main body of the device.

Fig. 6 is a transverse sectional elevation.

Fig. 7 is a plan view showing an extension strip sewed to a piece of leather.

In the preferred form of device I provide 60 a substantially double hollow V-shaped element pivotally attached to a universally adjustable member adapted to be secured to the bed plate of an ordinary sewing machine as by means of a screw, the adjustment being necessary to adapt the device to the varied machines in order that the proper relation may exist between this device and the needle and presser foot of the machine. Attached to the V element by adjustable 65 means is a guiding element which has a substantially V-shaped extension adjacent the inner portion of the hollow V element, the distance of spacing between these two members being regulated by a set screw carried 70 by the hollow V member. The material intended to be used as an extension to the leather or other material is fed through the hollow V member which automatically folds 75 the same. At the same time the leather or material to which the folded strip is to be sewed is pressed into the V-shaped guide, the set screw determining the overlap of the folded extension and the base material. The folded strip enclosing the base material 80 then passes beneath the presser foot of the machine and the two are sewed together in the usual manner.

Describing more in detail the preferred 85 form illustrated in the drawings, the numeral 1 represents the bed plate of an ordinary sewing machine which is usually provided with a screw threaded opening to which the various attachments may be secured. A screw 2 engages this screw threaded opening and secures to the bed plate the 90 universal element 3. It will be seen that the screw 2 engages the slot 4 in the part 3 so that the whole device may be adjusted in any direction. Pivotally secured to the part 3 as by means of pivot 5 and held against movement by a screw 5^a is an element which includes a hollow V-shaped portion 6 and a flared end, the front and back of the V portion 6 being separated as at 7 to allow 95 the material to readily pass into the hollow portion. Adjacent the opposite end of the part 6 is a nose 9 of a height sufficient to allow the turned up end of the presser foot to clear the same, but arranged to be adjacent the needle of the machine. That part 100 of the member 6 adjacent the nose 9 is ar-

ranged in the form of a narrow V in order to insure that the material is folded when it passes beneath the presser foot 10 to be sewed by the needle 11. The hollow V member increases from a narrow V adjacent the member 9 to a wide and open V at a point adjacent the lip 7. This larger lip 7 is provided with a broad curve which allows the extension material as it comes from a roll 10 or the like to engage the same naturally and pass into the narrower V portion without difficulty.

Attached to the upper portion of the hollow V member is a guide element having 15 an extension 12 provided with a right angular slot 13. A screw 14 having its shank passing through the slot 13 engages the upper portion of the hollow V member and allows the guide element to be adjusted in 20 relation to the hollow V member in the necessary directions. The main body 15 of the guide is substantially V-shaped, corresponding to the degree of closure of the hollow V element. This part 15 is disposed 25 within the open V of the hollow V member and has a portion 16 extending beyond the hollow V member and to a point adjacent the nose 9 thereof. The set screw 17 in the nose 9 determines the nearness of the part 30 16 to the nose 9, which determines the amount of overlap between the body material and the extension strip.

It will be apparent from the drawings that it is desirable to have the part 16 adjacent the needle 11 and so arranged that the presser foot will clear the same, as in the case of the nose 9. It will thus be seen that first the hollow V member or the device in its entirety may be readily adjusted by

means of the screws 2 and 5^a to get a rough 40 adjustment on any desired machine that will bring the nose 9 and the portion 16 adjacent the needle 11 and the presser foot 10. Final accurate adjustment may be made by regulating the set screw 14. The desired amount 45 of overlap between the base material and the extension strip may then be secured by manipulating the set screw 17, and as long as the base material contacts with the inner 50 face of the part 16, this definite overlap will occur and will occur with such regularity as to be automatic.

I claim:

1. A binder of the type described, including a hollow V element adapted to completely enclose an extension strip, a guide member adjacent to and extending within the open walls of the V member, and means carried by the V element to adjust the spacing between the guide and the hollow V member.
2. The device of claim 1, said hollow V member having a nose thereon, said adjusting means being carried by said nose.
3. The device of claim 1, said hollow V member having a nose thereon, adjusting means carried by said nose for spacing the guide from the nose.
4. The device of claim 1, said guide having an extension thereon extending beyond the hollow portion of the hollow V element.

In testimony whereof, I affix my signature.

HIRAM HOLDEN.
